(57) CLAIM

The ornamental design for a massage table, as shown and described.

DESCRIPTION

FIG. 1 is a perspective view of a massage table, showing my new design;

FIG. 2 is a top plan view thereof;

FIG. 3 is a side elevational view thereof, the opposite side elevational view being identical;

FIG. 4 is an end elevational view thereof; and,
FIG. 5 is an end elevational view thereof, opposite that shown in FIG. 4.

The bottom of the article is plain and unornamented.
